US00D702861S

(12) **United States Design Patent**
Boomgaarden et al.

(10) **Patent No.:** US D702,861 S
(45) **Date of Patent:** ** Apr. 15, 2014

(54) **LUMINAIRE**

(75) Inventors: **Mark Penley Boomgaarden**, Satellite Beach, FL (US); **Fred Kopitzke**, Satellite Beach, FL (US); **David Henderson**, Indialantic, FL (US); **Shane Sullivan**, Indialantic, FL (US); **Wei Sun**, Indialantic, FL (US)

(73) Assignee: **Lighting Science Group Corporation**, Satellite Beach, FL (US)

(**) Term: **14 Years**

(21) Appl. No.: **29/422,280**

(22) Filed: **May 18, 2012**

Related U.S. Application Data

(63) Continuation-in-part of application No. 29/410,099, filed on Jan. 4, 2012.

(57) **CLAIM**

We claim, the ornamental design for a luminaire, as shown and described.

DESCRIPTION

FIG. 1 is top perspective view of an exemplary embodiment of the invention;

FIG. 2 is a side view of the exemplary embodiment of FIG. 1, the luminaire being symmetric about a center axis;

FIG. 3 is a bottom view of the exemplary embodiment of FIG. 1;

FIG. 4 is a top view of the exemplary embodiment of FIG. 1; and,

FIG. 5 is a bottom perspective view of the exemplary embodiment of FIG. 1.

The phantom lines shown in FIG. 1-FIG. 5 are environmental and not part of the claimed design.

The color of the luminaire forms no part of the claimed design; a luminaire according to the claimed design may be of any color or combination of colors.

The surface treatment of the luminaire figures forms no part of the claimed design, a luminaire according to the claimed design may have any surface treatment.

1 Claim, 5 Drawing Sheets
